UNITED STATES PATENT OFFICE.

HIRAM HAVENS AND WILLIAM W. HAVENS, OF HARTFORD, CONNECTICUT,
ASSIGNORS OF ONE-THIRD TO AMOS WHITNEY AND WILLIAM N. WOOD-
RUFF, BOTH OF SAME PLACE.

WAGON-SEAT FASTENER.

SPECIFICATION forming part of Letters Patent No. 247,757, dated October 4, 1881.

Application filed April 23, 1881. (No model.)

To all whom it may concern:

Be it known that we, HIRAM HAVENS and WILLIAM W. HAVENS, of Hartford, in the county of Hartford and State of Connecticut, have invented certain new and useful Improvements in Wagon-Seat Fasteners; and we do hereby declare that the following is a full, clear, and exact description thereof, whereby a person skilled in the art can make and use the same, reference being had to the accompanying drawings, and to the letters of reference marked thereon.

Like letters in the figures indicate the same parts.

15 Our invention relates to a new and improved method of fastening the sliding seat of a wagon in any desired position, and its object is to provide a more easily adjusted and secure fastening than is now in use.

20 In the accompanying drawings, illustrating our invention, Figure 1 shows an outside view of the end of a wagon-seat and part of the top rail of the side of a wagon-body provided with our improvement. Figure 2 is an inside view 25 of the same: Fig. 3 is a cross-section through the clamping device, showing the details of the improved fastener.

A is the end support of the seat, which rests upon the top rail of the side-board B of the 30 wagon-body.

C is an outside plate attached to the end of the seat A, and extending downward so as to lap over the outer edge of the top rail, B.

D is an inside plate, attached to the end piece, 35 A, extending down over the inner edge of the rail B, as shown in Figs. 2 and 3. On the inside of the plate D is a spring, e, riveted to the

plate at its upper end, and reaching down so as to lap over the edge of the rail B, as shown in Fig. 3. Its lower end is made of a curved 40 form, so as to fit into a groove or channel, B', in the rail.

F is a set-screw turning in a hollow thread in the plate D, and pressing against the spring E to force it into the groove B'. 45

The operation of our improvement is as follows: When it is desired to move the seat the screw F is loosened and the seat slid along the top rail to any required position. While being moved it is held on the rail by the lower 50 lip of the plate C. The screw F is then turned in, which presses the spring into the channel B' and holds the seat from being moved along the rail or from being lifted up or loosened in any way. 55

To detach the seat entirely it is only necessary to fully turn back the screw, when the seat can be lifted off the side rails.

Instead of the seat sliding upon the top rail of the side, a separate rail can be attached upon 60 the inside of the side of the wagon-body, as is sometimes done, our improvement being applicable to any form of sliding wagon-seat.

What we claim as our invention is—

The combination of the plates C and D, the 65 spring E, and screw F with the end support A of a wagon-seat, and the rail B, provided with the groove B', substantially as described.

HIRAM HAVENS.
WM. W. HAVENS.
